UNITED STATES PATENT OFFICE.

WESTON GREEN, OF DAYTON, OHIO, ASSIGNOR TO THE GREEN & GREEN COMPANY, OF DAYTON, OHIO, A CORPORATION OF OHIO.

DESIGN FOR A BOX OR SIMILAR ARTICLE.

Application filed March 23, 1925. Serial No. 12,856. Term of patent 14 years.

To all whom it may concern:

Be it known that I, WESTON GREEN, a citizen of the United States, residing at Dayton, in the county of Montgomery and State of Ohio, have invented a new, original, and ornamental Design for a Box or Similar Article, of which the following is a specification, reference being had to the accompanying drawings, forming a part thereof.

In the drawings:

I claim:

The ornamental design for a box or similar article, as shown.

WESTON GREEN.
